INVENTOR;
Fred E. Moore;
BY Blakeslee & Brown,
ATTORNEYS.

UNITED STATES PATENT OFFICE.

FRED E. MOORE, OF LOS ANGELES, CALIFORNIA.

FURNITURE.

Application filed April 17, 1926. Serial No. 102,652.

This invention relates to furniture, and in particular to a novel form of chair which is so formed and constructed as to allow the occupant thereof to recline. The chair will then become useful as a couch or sleeping bed, as well as performing the function of a chair during the day time. The inventor is aware that there are chairs on the market in which the backs are capable of being tipped to different degrees relative to the seat, but so far as the inventor is aware in every instance no provision is made for the feet or limbs, save and except external stools or short extensions carried by the chair. The present invention contemplates a chair or article of furniture in which the cushioned effect of the chair is at all times maintained for the limbs, the torso and the head, when the chair is to be used as a couch.

In practicing the invention, I provide a chair having a seat, an auxiliary cushion member normally beneath said cushion portion of the seat when the furniture is acting as a chair as well as a cushioned back. The seat cushion may be drawn forwardly and maintained in such forward position by the chair frame and swinging leg members carried by the seat, and when the back of the chair is tipped, the auxiliary cushion member is raised to the level of the seat cushion which has been brought forward. The back may be maintained in an inclined position in any approved manner, such as providing legs therefor to hold the outer extremity in a definite position.

The invention has for an object the provision of an article of furniture which will perform a two-fold purpose, namely, that of supporting a person either in a sitting position or in a reclining position.

Another object is the provision of an article of furniture which may be utilized as a chair or as a couch, and in which all the cushioning members are self-contained upon the said article of furniture and so as to be at all times ready for instant use either as a chair or couch.

Another object is the provision of an article of furniture which is neat in appearance, efficient in operation, and generally superior in point of relative simplicity and inexpensiveness of construction.

With the above and other objects in view, the invention consists in the novel and useful provision, formation, construction, asso-

ciation and relative arrangement of parts, members and features, all as shown in one embodiment in the accompanying drawings, described generally, and more particularly pointed out in claims. 60

In the drawings:

Figure 1 is a side elevation of the chair; Figure 2 is a side elevation of the chair showing the back tipped, the cushioned seat drawn forwardly and a cushion member 65 normally beneath the seat raised to a position on a level with the cushioned seat and the back;

Figure 3 is a cross sectional view on the line 3—3 of Figure 5; 70

Figure 4 is a view similar to Figure 3 and showing the back tipped;

Figure 5 is a fragmentary plan view of the chair;

Figure 6 is a fragmentary elevation of the 75 chair looking in the direction of the arrow 6 in Figure 4;

Figure 7 is an enlarged detail of certain mechanism of the invention, the same being taken on the line 7—7 of Figure 8; and, 80

Figure 8 is an enlarged cross sectional detail of the invention on the line 8—8 of Fig. 3.

Corresponding parts in all the figures are designated by the same reference characters. 85

Referring with particularity to the drawing, the improved article of furniture is designated as an entirety by A, and the same includes a frame a, a back b, upper and lower seat members c and d, and mechanism designated generally as e adapted to move the lower seat member b to a given height relative to the frame a when the back b is tipped, all of which elements aforesaid are 90 used in practicing one embodiment of the invention. 95

In the present instance the article of furniture is shown as a chair, and which chair is provided with front and back supports or legs 1 and 2 respectively, a bottom frame member 3 having portions thereof extending between the legs for bracing the same and with arm members 4 extending between the respective front and back leg members. 100 Other bracing means for the legs may of course be provided, as is customary. The back member is hingedly united at 5 to the legs 2 and whereby the back may be tipped 105 relative to the frame. This back member 110

is directly associated with the means *e*, there being one of said means for each chair side, and as said means *e* is identical for each side, only one of the said means will be described.

Referring to Figure 3 a track-way 6 which is of channel formation extends from the front leg 1 to the rear leg 2, and in a downward direction from the front leg to 10 the rear leg. The bottom leg member of such track-way is cut away at 8 and a member 9 extends from the upper leg 10 of such track-way and is bent beneath the other leg, as shown at 11, see Figure 7. Likewise constituting a part of the means *e* are two further track-way members mounted in spaced parallelism beneath the lower seat member *d*, as shown at 12. These track-ways are likewise of channel formation. A bell crank 15 lever 13 has the short end thereof pivoted at 14 to the front of the chair frame, and the terminal portion of the long arm thereof carries a roller 15 received in the track-way 12. A rear bell crank lever 16 is pivoted 20 at 17 at a rear portion of the chair frame, the pivot pin lying at the bend between the long and short levers of such bell crank lever, and the long lever thereof carries a roller 18 receivable in the track-way 12. A link 19 is pivoted to the short length lever of the bell crank lever 16 at 20, and the opposite end of such link is pivoted at 21 at the bent portion between the long and short arms of the bell crank lever 13. A link 22 30 is pivoted at one end 23 to the back *b* and the opposite end is pivoted at 24 to the bell crank lever 16 and specifically to the long lever arm thereof.

The upper seat member *c* carries adjacent 40 the base portion thereof and at the rearward end thereof, two side extensions 26. The extensions being identical, only one will be described, and reference is made to Figure 8. This extension includes a strap 27 received 45 in a guide 28, the guide being secured to a side of the seat *c*, and end of said extension carrying a roller 29, the roller being received within the track-way 6. The said strap is slotted longitudinally at 30, and a pin 31 is 50 secured to the guide 28 and passed through the slot for limiting outward or inward movement of the strap relative thereto. The outer extremities of the frame of the seat *c* carry pivoted legs 32, said legs being of the 55 telescoping type so that the same may be adjusted as to the height that they hold the seat *c*, as indicated in dotted and solid lines of Figure 2. Likewise the back *b* carries pivoted legs 33 whereby the same may be 60 maintained in a given inclined position relative to the frame *a*. The back is so formed as to allow the legs 33 to be received within the cushion portion thereof as indicated at dotted lines in Figure 1 when the device is 65 acting as a chair. It is intended that the

back as well as the upper and lower seats, or what may be termed main seat and sub-seat should be cushioned as illustrated fragmentarily at 34 in Fig. 5. To this end it is of course realized that the back, main seat and sub-seat would be provided with framing, as illustrated for the seats at 35 and 36 to properly support the springs and padding thereof.

The operation will be readily apparent 75 from the following brief statement: Assuming that the chair is of the appearance shown in Figure 1 and it is desired to convert the same into a couch, the main seat *d* is drawn forwardly from the position shown 80 in Figure 1 to the position shown in Figure 3 at 37, and it will be seen that the roller 29 carried by the strap 27 will follow the track-way 6 and be prevented from escaping from said track-way by the end-piece 9 shown in 85 Figure 7, the roller 29 dropping into the cut-away or interrupted portion 8 of the lower leg of the track-way. The legs 32 may then be dropped into position as shown in Figs. 2 and 4. The back *b* may then be tipped 90 and this tipping will raise the sub-seat or bottom seat member upwardly to where it is on the level with the inner end portion of the seat *c*. It will be remembered that the link 22 is connected to the arm 16, and that a roller 18 is carried by the said arm 16, which roller is within the track-way 12. When the back *b* is tipped at its hinge connection 5 relative to the back supports or legs of the chair, the link 22 will revolve the arm 16 about the pivot point 17, and the lower end of such lever will move the link 19 forwardly. As this link is pivoted at 21 to the lever 13 this lever 13 will be revolved from a lower to an upper position about its pivot 105 point 14, and as the upper extremity of such lever carries a roller 15 within the track-way 12, an upward movement of the front and rear levers, namely, 13 and 16, will by their travel within the track-way 12 raise the sub-seat. The legs 33 may be dropped from the back so as to hold the back inclined. As a stabilizing medium for the sub-seat I have provided means *f* which includes two straps 110 40 and 41 hinged at 42 with the lowermost end of the strap 41 hinged to the bottom frame at 43 and the upper end of the strap 40 hinged at 44 beneath the track-way 12. Two of such hinges are provided, one for each side of the sub-seat. It is intended that 115 these straps should be relatively wide so that the sub-seat will be prevented from forward or backward movement and thus the sub-seat maintained in a definite position without being unstable.

It is obvious that various changes and modifications may be made in practicing the invention, in departure from the specific showing of the drawing, without departing 120 from the true spirit of the invention.

Having thus disclosed my invention, I claim and desire to secure by Letters Patent:

1. Improvements of the character disclosed, comprising a frame, first and second cushion members normally positioned one above the other, a cushion back hinged to said frame, guide means between the said frame and the uppermost cushion member whereby said uppermost cushion member may be extended forwardly relative to the frame member, guides carried by the lowermost cushion member and means receivable in said guides and associated with the back whereby when the back is tipped relative to the frame member, said lowermost cushion member is raised a determined distance relative to the frame.
2. Improvements of the character disclosed, comprising a frame, first and second cushion members normally positioned one above the other, a cushion back hinged to said frame, guide means between said frame and the uppermost cushion member whereby said uppermost cushion member may be extended forwardly relative to the frame member, guides carried by the lowermost cushion member and means receivable in

said guides and associated with the back whereby when the back is tipped relative to the frame member said lowermost cushion member is raised a determined distance relative to the frame; there being separate means for the uppermost cushion member and for the back for maintaining the uppermost cushion member in extended position and the back in its tipped position.

3. A chair capable of being converted into a couch, including a frame, supporting legs therefor, a back hinged to said frame, upper and lower seat members normally positioned one above the other when acting as a chair, front and rear bell crank levers pivoted to the said frame and secured to the lowermost seat member, links between the bell crank levers and the back, guide means between said frame and said uppermost seat member and whereby when the uppermost seat member is extended forwardly of the said frame, and the back tipped, the lowermost seat member is raised to position the same in substantially alignment with the extended seat member.

In testimony whereof, I have signed my name to this specification.

FRED E. MOORE.
